CASTING MACHINE

John F. Crawford, Racine, Wis., assignor to J. I. Case Company, Racine, Wis., a corporation

Application February 26, 1940, Serial No. 320,735

20 Claims. (Cl. 22—65)

The present invention relates to casting machines and more particularly to such as are intended for casting sleeves or other hollow forms.

An object of the invention is to generally improve the construction and operation of devices of this class. A further object is to provide such a machine which will have a relatively large capacity.

Further objects are to provide such a machine having a rotatable flask in which castings may be made repeatedly and as rapidly as they are sufficiently cooled to stand being removed from the mold; to provide methods and mechanism for forming a sand mold within the rotating flask immediately after each casting is discharged therefrom; to provide a movable carriage for supporting the rotatable flask and disposing it in various positions or attitudes best adapted for the various operations; and to provide suitable facilities and expedients for the realization of the above objects.

An illustrative embodiment of the machine is described in the following specification and illustrated in the accompanying drawings in which Figure 1 is an axial vertical sectional view taken through the characteristic parts of the machine.

Fig. 2 is a similar view of a portion of Fig. 1 showing the parts in a different position.

Figs. 3, 4, 5, 6 and 7 are similar views with other parts removed, showing the parts in various other positions and illustrating various steps in the process of casting a cylinder sleeve.

Fig. 8 is an elevation taken from the opposite side of the machine from that shown in Fig. 1 and with parts broken away.

Fig. 9 is an enlarged sectional view on the line 9—9 of Fig. 8.

Fig. 10 is an enlarged sectional view on the line 10—10 of Fig. 5.

Returning to Fig. 1, the machine in general comprises a base B upon which is mounted for rotation in the present instance about a shaft or axis A, a carriage generally designated as C. Carriage C supports rotatable flask F, a motor M for rotating the flask and various mechanism, and expedients to be more fully described below.

Base B also supports a guide, ram, or secondary carriage G for cooperation with flask F in a manner to be presently explained, the carriage C being rotatable for placing the flask in the various attitudes indicated in Figs. 1 to 7, for accomplishing the various steps in the casting of a sleeve.

Motor M is supported as by a suitable bracket 1 from a clamp-block or the like 2, in the present

instance fixed with shaft A. Block 2 carries an arm or support 3 in turn supporting a bearing head or the like, generally designated as 4, head 4 and motor M constituting the major portions of carriage C. Shaft A also has fixed thereon in a position convenient for operation, a hand wheel or similar manually operable element 5 and an indexing plate 6, Fig. 8, providing notches as 7 engageable in well-known manner with a detent or dog 8 pivoted on a stud 8^a or the like carried by any convenient fixed part of the machine for suitably locating carriage C in the various necessary attitudes.

Motor M drives, through a pulley or the like 9, belts 10—10 and a pulley 11, a spindle or stem 12 journaled in head 4 as by means of anti-friction bearings 13 and 14, Fig. 1, of any suitable or preferred type. Spindle 12 may have a flange 15 engaging a base or attaching portion 16 of flask F, and which may be removably secured thereto in any suitable or well-known manner. In the present instance, bolts as 17 pass through flange 15 and a reinforcing ring or housing 18 enclosing a portion of head 4 and assisting in preventing access of dirt or the like to bearing 14. By removing bolts 17, other flasks of different sizes or characteristics may be substituted for flask F for adapting the machine to different styles of castings, although it is to be understood that one flask remains in place throughout numerous successive casting operations, the molds being formed directly in the flask and removed and renewed repeatedly as the operation continues.

Flask F carries a retaining flange or closure 19 having an inwardly extending lip 20 and being readily removable from the flask as by means of a "bayonet" slot 21, Fig. 6, engaging a pin 22, or other suitable or well-known expedients for holding such a closure in place.

With the mechanism so far described, it will be apparent that, through the operation of motor M, spindle 12 and flask F may be given a rapid rotating movement about the axis of flask F and spindle 12, and, through the hand wheel 5 the entire carriage, including the motor and drive, may be rotated about shaft A to dispose said axis in any desired position without interrupting the rotation, notches 7 being provided in index plate 6 to hold the parts in the attitudes necessary for the operation.

Spindle 12 is hollow in the present instance and carries therein mechanism for actuating a strike or ejecting head generally designated as 23. This mechanism comprises a piston 24 slid-

able in fluid tight relation to the bore 25 of spindle 12. Piston 24 is fixed in the present instance with a tubular stem 26 extending lengthwise of the plunger and through a suitable closure or packing 27 into the interior of flask F and being fixed in suitable manner as by a threaded connection 28 with above mentioned head 23.

Piston 24 is also slidable in fluid tight relation on the outer surface of a tube or pipe 29 extending through the major portion of the length of the spindle 12, and ports as 30 in tubular stem 26 provide for flow of fluid from pipe 29 into the bore of spindle 12 about stem 26. Pipe 29 is fixed with a fitting 31 extending into the end of spindle 12 remote from flask F, the space about the fitting being closed by a packing or other sealing means 32 to provide for rotation of spindle 12 about fitting 31 without the escape of fluid therefrom. Fitting 31 may have a flange 33 for preventing endplay of spindle 12 as seen in Fig. 1. Fitting 31 is prevented from rotating as by a member 34 clamped or otherwise fixed on the fitting as by a screw 35 and supported from bracket 3 by one or more rods as 36.

A bore 37 in fitting 31 communicates with the bore 25 of spindle 12 exteriorly of pipe 29 and communicates as by a port 38 with a conduit 39 for pressure fluid. A bore 40, also in fitting 31, communicates with pipe 29 and through a port 41 with a conduit 42 also for pressure fluid.

It will now be apparent that supplying pressure fluid through conduit 39 and exhausting it through conduit 42 will cause movement of piston 24, stem 26 and head 23 to the left as seen in Fig. 1. Supplying of fluid through conduit 42 and exhausting through a conduit 39 will cause opposite movement of piston 24 and its attached parts. Head 23 is so advanced through flask F for the purpose of preliminarily forming the mold and also form ejecting the finished casting as will appear.

Base B, in addition to supporting shaft A, carries supports or partitions 43, 44 and 45 which cooperate for carrying and actuating a tamping or finishing roller generally designated as 46, for insertion and operation within flask F at one stage in the making of each mold. In the present instance partition 43 carries tubular element or stem 47. Stem 47 carries a piston 48 about which is slidable in fluid type manner a cylinder or hollow plunger 49, cylinder 49 being also slidable within a collar or fitting 50 fixed with partition 44. In this manner cylinder 49 may be extended through partition 44 for a substantial distance without support other than engagement with collar 50 and piston 48. The end of cylinder 49 at the left as seen in Fig. 1, is closed by a packing or other suitable element 51, slidable in fluid tight manner on the exterior of stem 47, element 51 cooperating to guide and direct cylinder 49.

Cylinder 49 carries a flange 52 to which is fixed a fitting 53 having a guide portion 54 which may conveniently be a flange for cooperation with flange 52, suitable bolts or other fastenings 55—55 serving to secure the parts together. Fitting 53 carries a roller support including a shank 56 which may conveniently be coaxial with cylinder 49, a flange 57 which may be coaxial with shank 56, and an axle portion 58 which is offset from shank 56. Roller 46 is journaled on axle 58 as by bushings or other suitable or well-known means 59 and 60, to be freely rotatable thereon.

Stem 47 and cylinder 49 in the present instance are offset from the axis of spindle 12, when

in the position of Fig. 1, to an extent less than the offset of axle 58 relative to shank 56, although other means is contemplated for offsetting roller 46 when desired.

5 Flange 54 of fitting 53 is adapted to fit within guide or collar portion 61 carried in partition 45 to guide the fitting and prevent displacement thereof under the considerable side thrust developed in forming the mold. Flange 54 is so 10 formed as to be freely rotatable within collar 61 when guided therein, and flange 57 is suitably fixed with fitting 53, as for example by a pin or the like 62.

Cylinder 49 has fixed therewith as by a clamp 15 63 engaged with the cylinder as by a screw 64, an actuating handle or element 65, by means of which cylinder 49 may be rotated through a fairly large arc, in the present instance approximately 180°.

20 Stem 47 provides ports as 66 adjacent piston 48 and a conduit 67 extending through the stem and through piston 48 to communicate with the space to the right of piston 48 as seen in Fig. 1. A fitting 68 is engaged with stem 47 at the left end thereof and has a bore 69 communicating with the interior of the stem 47 and, through a clamp 70, fixed with fitting 68 as by a screw 71, with a conduit 72. Another bore 73 communicates with conduit 67 and through clamp 70 with a conduit 74. By supplying pressure fluid through conduit 72, pressure may be communicated through stem 47 and ports 66 to the space between fixed piston 48 and packing 51, causing movement to the left of cylinder 49 together with fitting 53 and roller 46, thus retracting roller 46 from the interior of flask F, roller 46 having previously been shifted to a position where it will clear collar 20, as follows:

Starting with the position of the parts shown in Fig. 1, cylinder 49 is rotated by means of handle 65 to offset axle 58 upwardly instead of downwardly relatively to cylinder 49. Owing to the slight downward offset of cylinder 49, roller 46 will thereby be brought substantially coaxial with flask F, or at any rate into a position in which it may be retracted to the left as seen in Fig. 1.

On the other hand, supplying pressure fluid through conduit 74 and exhausting it through conduit 72, as will further appear, develops pressure between fixed piston 48 and the end of cylinder 49 formed by flange 52, thereby displacing cylinder 49 to the right. Assuming roller 46 for the time being to be positioned coaxially with flask F, this movement will result in inserting roller 46 within flask F, at the end of which movement flange 52 will contact collar 61 and locate the roller properly within the flask while flange 54 will seat within collar 61 to brace the structure against side thrust. Handle 65 may then be actuated to offset the roller for rolling or compacting the mold being formed within flask F as will further appear.

The several steps in the casting of a sleeve may now be understood from the mechanism so far described. Referring to Fig. 2, flask F is first positioned with its axis vertically, head 23 being retracted and forming the bottom wall in flask F in this position, the head being contoured to form the desired distribution of the molding sand in this region. A predetermined quantity of suitable molding sand which may be of any suitable or well-known composition, core sand having been found satisfactory, is introduced into the flask as by a funnel or the like 75, the flask being first started rotating or spinning by

means of motor M. Owing to the rotation of flask F, the sand will be thrown outwardly by centrifugal force and distributed within the flask approximately in the manner indicated.

The flask continues to rotate throughout the succeeding steps of the process.

Carriage C is then rotated or indexed to the position shown in Fig. 3, head 23 then being advanced as above described and forming a path through the sand so as to leave it distributed in flask F in an even layer 76, maintained in place in the flask by the above mentioned centrifugal force. The excess sand is thrown out through the retaining flange 19, a shield 77 keeping the sand within the confines of the machine. Centrifugal force alone keeps the layer of sand 76 in place at this stage of the operation.

When the plunger 23 has traversed the length of the flask, it is retracted to its original position as shown in Fig. 4, leaving layer 76 complete and of predetermined thickness throughout the length of flask F. When plunger 23 is completely retracted, cylinder 49 is advanced by fluid pressure as above outlined, placing roller 46 substantially concentrically within flask F and its lining of sand 76. Handle 65 is then manipulated to rotate cylinder 49 as above described, offsetting roller 46 to the position shown in Fig. 1, reducing the thickness of sand layer 76 and compacting it to the necessary density for receiving the molten metal. Roller 46 has a collar 78 which forms a groove 79 in the sand for forming an attaching flange on the finished sleeve. Other configurations for roller 46 and also for flask F for forming sleeves of varying types or cross sections, are contemplated as part of the invention.

The sand mold or lining is now complete and may possibly undergo a certain amount of baking from the residual heat in flask F, although this does not appear to be essential for the successful operation of the apparatus. Roller 46 is returned to retraction position shown in Fig. 4, and backed out of the mold by means of fluid pressure, whereupon carriage C is rotated or indexed through substantially 180° to the position shown in Figs. 5, 6 and 8.

A spout 80 hinged on a suitable support 81 is swung into place with delivery spout 82 projecting within the opening in flange 20, whereupon a measured quantity of molten iron or other suitable metal, which will give the desired properties in the casting, is poured into spout 80 and, owing to the centrifugal force developed by the continued rotation of flask F, with its sand lining 76, arranges itself in the form of a tube or sleeve within the accurately formed inner surface of the sand lining 76, the sleeve having an accurately formed cylindrical interior or bore 83, Fig. 6.

The heat of the molten metal liberates quantities of gas from the moist sand, as is understood, which gas escapes through openings or vents 84-84, formed through the outer wall of flask F. These openings being of any desired shape but preferably flaring outwardly so that they tend to clear themselves of accumulations of sand rather than to become packed with the same, and thereby closed. Additional openings 85, similar in character, are provided in flange 20 for a similar purpose. Flask F is allowed to continue to rotate until the interior of the newly cast sleeve 86, as observed through the opening in flange 20, has acquired a color indicating that it has cooled enough to support itself. The rotation of flask F is then stopped and collar 19 removed in any

suitable manner, as by tapping on a lug 87 to dislodge it from pins 22, whereupon carriage C is indexed to place flask F in the position as shown in Fig. 7. Plunger 23 is then advanced slightly as by fluid pressure as above described, which movement breaks part of the sand lining and exerts a substantial pressure on the inner, or what is then the upper end of sleeve 86, which falls out of flask F together with most, if not all of the sand lining.

Carriage 12 is then indexed again to the position of Fig. 5 and the interior of flask F is cleaned in any suitable manner, as by a swab or the like, or while still in the position of Fig. 7 the flask may be cleaned by the insertion of a finger 88 guided for vertical movement by suitable or well-known means not shown, the flask being set rotating again for this purpose. Finger 88 is so placed that sleeve 86 will clear it when dropping out of the flask, and movement may be imparted to it by hand or otherwise through suitable or well-known connections not shown.

With the carriage in the position indicated in Figs. 5, 6 and 8, collar 19 is replaced, motor M again started to resume the rotation of flask F whereupon the cycle is repeated, in actual practice a completed sleeve being turned out of the machine about once in every five minutes or less.

The foregoing is an explanation of the characteristic features and principles involved in the invention. Numerous expedients are used for accomplishing the various above outlined operations, many of which are well-known but which will be described in order to provide a complete working illustrative embodiment. For example, in the present instance to prevent flask F from becoming overheated, it is provided with flanges 89-89 which provide a large radiation surface and help to control the temperature of the flask. If desired, a nozzle 90 may be hinged to support 81 or other suitable supporting means and arranged for blowing compressed air or other cooling fluid directly into the mouth of flask F for cooling the castings or the flask or for blowing bits of sand out of the flask, or for other purposes.

Head 23, in order to prevent transmission of excessive heat to stem 26 and accordingly to the fluid actuating the stem and piston 24, is made in two or more pieces, as 91 and 92, which are united by bolts or the like 93 and formed to provide a cavity 94 within the head for partially isolating portion 91 from portion 92. Conversely, the making of plunger 26 hollow, and causing the circulation of the fluid therethrough by means of pipe 28, on its way to the space of spindle 12 carries away a large amount of heat from portion 92 and assists in preventing its reaching excessive temperature. This is important inasmuch as portion 91 is exposed directly to the interior of the newly cast sleeve without the benefit of any sand lining, the latter ending at the outer periphery of head 23 as clearly apparent from Fig. 1.

Pressure fluid is supplied for the actuation of piston 24 and cylinder 49 as follows: Fluid, for example oil, is contained in a reservoir 95, Fig. 8, and put under pressure in a conduit 96 as by any suitable pump 97, driven through a belt or the like 98 by a motor 99. Conduit 96 may, for example, lead to a branch 100 connecting with one or more control valves, in the present instance two, although a single valve is contemplated having different positions for the separate functions of a machine. Hydraulic pumps, valves, etc., be-

ing well known, it is unnecessary to describe these elements in detail other than to point out the particular functions that they serve in this organization.

A control valve 101 receives fluid through a conduit 102 communicating with branch 100 and, according to its adjustment, may transfer it through either of conduits 103 and 104, at the same time receiving fluid returning through the other conduit and exhausting it through a conduit 105, connecting with a branch 106 leading to a discharge or return pipe 107 emptying into reservoir 95.

In like manner, a control valve 108 receives fluid through a conduit 109 also communicating with branch 100 and discharges it through either of conduits 110 or 111, connecting respectively with above mentioned conduits 72 and 74. Fluid returning from the other conduit is exhausted through a conduit 112 communicating with conduits 105 and 107. These valves 101 and 108 control the actuation of head 23 and cylinder 49. A relief valve 111^a provides communication between conduits 100 and 107 and may be adapted to open automatically in the event of the development of excess pressure or under other desirable conditions.

Conduits 103 and 104 must communicate with above mentioned conduits 39 and 42 on carriage C which as above described is rotatable about the axis of and in fact with axle A. To provide for this, axle A, Fig. 9, is preferably although not necessarily tapered as at 113, and a fitting generally designated as 114 is fitted in a fluid tight manner on the tapered surface. Fitting 114 provides grooves or channels 115 and 116 surrounding or at least partially surrounding axle A. Above mentioned conduit 103 communicates in any suitable manner with channel 115 while conduit 104 communicates with channel 116. Axle A has a port 117 which registers with channel 115 and communicates with a bore 118 leading longitudinally of the axle to a point beyond a bearing 119 carried by base B and serving in part to support axle A. Another port 120 communicates with above mentioned conduit 39 on carriage C.

In a similar manner a port 121 in axle A communicates with channel 116 and leads into a bore 122 which in turn communicates with a port 123 connecting with above mentioned conduit 42. In this manner fluid communication into the movable carriage is obtained so that piston 24 and head 23 will respond to the position of valve 101. Valve 101 may be controlled by a suitable handle or other manually operated member 124, Fig. 1.

Conduits 72 and 74 as above described lead directly to fitting 68 and accordingly cylinder 49 will respond to the position of valve 108. Valve 108 has a handle or similar means 125.

Valves 101 and 108 may be of any suitable or well-known construction, such that controls 124 and 125 will have a neutral position in which no fluid will flow in the conduits controlled thereby, or other well-known or suitable characteristics such that piston 24 and cylinder 49 may be advanced or retracted or held in any desired position at will by appropriate manipulation of controls 124 and 125.

Referring again to flask F, provision is made for preventing transmission of excessive heat to spindle 12. For this purpose portion 16 is substantially enlarged in the present instance over the diameter of the major portion of the flask. Portion 16 is also formed with a cavity 126 so that there is no direct contact of any appreciable

area between portion 16 and flange 15. Furthermore, parts of portion 16 are cut away as indicated at 127 between above mentioned screws 17, to further reduce the area of contact between the flask and flange 15. In this manner flask F is to a certain extent isolated from spindle 12 and does not communicate thereto more heat than can be effectively carried away by fluid circulating within spindle 12. The fluid and spindle accordingly maintain a safe and efficient operating temperature.

Dog 8 may be controlled in any suitable or convenient manner, in the present instance a pull rod 128, Fig. 8, being pivoted to the dog at 129 and extending to a clevis 130 pivoted as by a pin 131 to a lever 132 fulcrumed on a pin 133, carried as by a bracket 134 on base B. Rod 128 may be upwardly urged by any suitable means, such for example as a spring 135 compressed between a collar 136 on rod 128, and some fixed element such as a bracket 137 on base B. Lever 132 may extend through base B and constitute a foot pedal 138, Fig. 1. Thus the operator may have both hands free to control hand wheel 5 while dog 8 is released on pressure of 138.

Spout 80 is arranged so that spout portion 82, as seen in Fig. 10, is offset from the vertical plane of the center line of flask F and toward the side of the sand lining 76 which is moving downwardly by virtue of rotation of the flask. In this manner the molten metal obtains a component of movement by its fall from spout 82 in the general direction of movement of the sand mold. It is unnecessary for the sand lining to assume the entire burden of starting the rotation of the metal from its relatively stationary or only slightly moving condition as it leaves the spout 82. Such a requirement might, under certain conditions, result in a washing away of the sand lining and enlargement of imperfection in the casting in the region where the metal first contacted the sand. This offset or substantially tangential introduction of the fluid metal eliminates this possibility.

Electric current for operation of motor M may be introduced into carriage C in any suitable or well-known manner, in the present instance slip rings 139 and 140 being mounted upon a body 50 of insulation 141 fixed in any suitable or well known manner on axle A. A wire or other conductor 142 connected with slip ring 139 and leading into a central bore 143 in axle A, extends through the bore and a bore 144 within base B 55 to a terminal box 145 or other suitable point of connection with motor M. A second insulated wire 146 extends from slip ring 140 through bores 143 and 144 and also to terminal box 145 as above. Brushes 147 and 148 bear resiliently 60 against slip rings 139 and 140, urged by any well-known or suitable expedient not shown and connect with leads 149 and 150 leading from a switch 151 connected to a suitable source of energy 152. Leads 152^a and 153 also lead from switch 151 to 65 a terminal box or the like 154 on motor 99. With the mechanism above described, the various steps for casting a cylinder sleeve can be carried out as hereinbefore explained. Thus, motor 99 may be operated through the source of energy 151, supplying fluid pressure to valves 101 and 108 for controlling piston 24 and cylinder 49. Carriage C may be released for rotation by pressure upon pedal 138 and the carriage may be turned and controlled when so released by hand 70 75 wheel 5.

Excessive heat is prevented from being transmitted to spindle 12 by the limited area of contact of flask F with flange 15. Washing of the sand lining is prevented by the substantially tangential delivery of the fluid metal through spout 82. Fluid pressure is communicated through rotating axle A, and accordingly to piston 24 through fitting 114 and electrical energy for the operation of motor M is introduced through slip rings 139 and 140.

The above being a complete description of a workable illustrative embodiment of the invention, what is claimed as new and desired to be secured by Letters Patent of the United States is:

1. In a casting machine, a sleeve-like flask rotatable about its axis and having an open end, a movable plunger normally disposed at the opposite end of said flask from said open end, means disposed adjacent the open end of said flask in one position thereof for introducing sand into the open end of said flask, said plunger being adapted to traverse said flask and expel excessive sand through said open end for forming preliminary rough molds within the flask, means for retracting said plunger, a roller carried by the machine and adapted for introduction through said open end in one position of said flask and to be offset for compacting said mold and forming a finished molding surface, means for retracting said roller, means for introducing molten metal into said finished mold, and means for releasing the resulting casting and the used sand.

2. In a casting machine, a sleeve-like flask having an open end, means for rotating the flask about its axis, means for swinging the flask while rotating to an upright position with the open end up, means disposed adjacent the open end of said flask in one position thereof for introducing sand into the open end of the rotating flask, means for expelling surplus sand from the rotating flask and forming a rough mold therein, means positioned and adapted to be introduced into said flask and displaceable for compacting said sand and forming a finished mold, means for locating said flask with its axis in position for receiving molten metal into said mold, means for introducing metal into said mold, means for releasing the resulting casting and used sand when cooled and means for ejecting said casting.

3. In a casting machine a sleeve-like flask having an open end, means for rotating the flask about its axis, means disposed adjacent the open end of the flask for introducing sand into the open end of the rotating flask, means adapted to be introduced into the rotating flask from the opposite end from the said open end for expelling surplus sand through said opening, means introduceable into the flask through said open end for compacting the sand and forming a mold within said flask while the rotation continues, and means for pouring molten metal into the mold thus formed for forming a casting within said mold.

4. In a casting machine a sleeve-like flask having an open end, means for rotating the flask about its axis, means supported adjacent the open end of the flask for introducing sand into the flask while the same is rotating, and means adapted to be introduced into the rotating flask to urge surplus sand toward and out of the open end thereof.

5. In a casting machine a rotatable spindle, a flask carried by said spindle, a fluid motor in said spindle, a plunger carried by said spindle, so disposed as to be actuated by said fluid motor

and having a head normally at one end of the flask, and adapted to be introduced into said flask, during rotation of the spindle and flask by said fluid motor, and a source of fluid under pressure connected with said fluid motor for actuating said fluid pressure actuated element.

6. In a casting machine, a sleeve-like flask rotatable about its axis and having an open end, closing means partially closing said open end, a movable plunger normally disposed at the end of said flask opposite said open end, means for causing said plunger to traverse the length of said flask, means supported adjacent the open end of said flask for introducing sand into the open end of said flask, said plunger being adapted to expel excessive sand through said open end, means for retracting said plunger, means for compacting the remaining sand and forming a finished mold surface, means for introducing molten metal into the finished mold, means for releasing said closing means for releasing the resulting casting and used sand, and said plunger being adapted to be advanced to expel said casting from the flask.

7. In a casting machine a sleeve-like flask rotatable about its axis and having an open end, means supported adjacent said flask for substantial registration with said open end for introducing sand into said flask for forming a mold therein, pressure exerting means insertable within said sleeve-like flask for compacting the sand and forming a finished mold within the flask, and said flask providing a plurality of outwardly flared vent holes for the escape of gases developed in the sand mold, the size of said holes being so chosen as to provide for the escape of excessive sand to prevent undue compacting of the sand by said pressure exerting means, and means for introducing molten metal into said mold.

8. In the centrifugal casting of molten metals by subjecting a mold charged with molten metal to the effect of rotation in a casting machine, the steps of rotating a flask and while rotating charging the flask with sand to be acted upon by centrifugal force, scraping the sand to a substantially uniform thickness, pressing the sand, charging the finished mold with molten metal and continuing the rotation of the mold while the metal sets.

9. In the centrifugal casting of molten metals by subjecting a mold charged with molten metal to the effect of rotation in a casting machine, the steps of rotating a flask and while rotating charging the flask with sand to be acted upon by centrifugal force, scraping the sand to a substantially uniform thickness, pressing the sand to produce a suitable density and form, charging the finished mold with molten metal and continuing the rotation of the mold while the metal sets.

10. In the centrifugal casting of molten metals by subjecting a mold charged with molten metal to the effect of rotation in a casting machine, the steps of rotating a flask with its axis in an upright position and while rotating charging the flask with sand to be acted upon by centrifugal force, scraping the sand to a substantially uniform thickness, pressing the sand to produce a suitable density, shifting the mold to a substantially horizontal position, charging the mold with molten metal and continuing the rotation of the mold while the metal sets.

11. In the centrifugal casting of molten metals by subjecting a mold charged with molten metal to the effect of rotation in a casting machine,

the steps of rotating a flask with its axis in an upright position, and while rotating charging the flask with sand to be acted upon by centrifugal force, shifting the flask to a substantially horizontal position, scraping the sand to a substantially uniform predetermined thickness, pressing the sand to produce a suitable density and to accurately form the desired internal contour of the mold, charging the finished mold with molten metal, continuing the rotation of the mold while the metal sets, shifting the mold to a downwardly directed position, ejecting the casting and sand and repeating the cycle while the flask retains sufficient residual heat to assist in hardening the sand.

12. In the centrifugal casting of molten metals by subjecting a mold charged with molten metal to the effect of rotation in a casting machine the steps of rotating a flask and while rotating charging the flask with sand to be acted upon by centrifugal force, scraping the sand to a predetermined thickness, pressing the sand to a suitable density, charging the finished mold with molten metal, continuing the rotation of the mold while the metal sets, ejecting the casting and sand and repeating the cycle while the flask retains sufficient residual heat to assist in hardening the following charge of sand.

13. In a casting machine a flask of open ended sleeve like form rotatable about its axis, means on the machine for supporting the flask and shiftable for disposition of its axis at various angles relative to a horizontal plane suitable for consecutive operations in forming a mold and casting within the flask, means on the machine cooperating with the flask in each position thereof for performing an operation requisite to forming therein finished molds and castings, and said flask having means partially closing the open end and movable away from said end for releasing castings formed in the flask.

14. In a casting machine a rotatable spindle, a flask carried at one end of the spindle for rotation therewith, means for permanently fastening the flask to the spindle, said means being so shaped as to limit the area of contact available for transmission of heat from said flask to said spindle, and fluid motor means in said spindle for carrying away heat absorbed from said flask.

15. In a casting machine a sleeve like flask rotatable about its axis and having an open end, a movable plunger normally disposed at the opposite end of said flask from said open end, means partially closing the open end and movable away from said end for releasing castings formed in the flask, means disposed adjacent the open end of said flask in one position thereof for introducing sand into the open end of said flask, said plunger being adapted to traverse said flask and expel excessive sand through said open end for forming preliminary rough molds within the flask, means for retracting said plunger, a roller carried by the machine and adapted for introduction through said open end in one position of said flask and to be offset for compacting said mold and forming a finished molding surface, said roller being dimensioned and constituted to displace some of the sand formed in the preliminary rough mold against said means partially closing said open end to protect it from contact with

molten metal, means for retracting said roller, and means for introducing molten metal into said finished mold.

16. In a casting machine a sleeve like flask rotatable about its axis and having an open end, a flange adapted to partially close said open end and movable away from said flask for releasing the contents thereof, means for introducing sand into said flask and means for compressing sand for forming a compact finished molding surface within said flask, and said compressing means being constituted and adapted for displacing some of said sand against said flange for protecting it from damage from molten metal, and means for introducing molten metal into said finished mold.

17. In a centrifugal casting machine, a flask, rotatably supported on the machine, having an open end and adapted to contain a sand mold, means supported on the machine positioned for introduction into said flask for forming a sand mold in the flask while the same is rotating, separate means also carried on the machine in position for introduction into said flask for compressing the sand for forming a hard molding surface, means positioned for introduction into the flask for pouring molten metal into the mold for forming a casting therein, said flask being adapted to contain said sand mold and said casting and to confine material urged by centrifugal force within said flask, and having a displaceable part adapted to be moved to release said sand mold and casting from the flask.

18. In a casting machine, a flask of sleeve-like form rotatable about its axis and having an open end, said flask being shiftable for disposition of its axis at various angles to a horizontal plane, and said flask having means partially closing the open end and movable away from said end for releasing castings formed in the flask.

19. In a casting machine, a rotatable spindle, a flask carried by said spindle, a fluid pressure actuated element in said spindle, a plunger carried by said spindle, so disposed as to be actuated by said fluid pressure actuated element and having a head normally at one end of the flask, and adapted to be introduced into said flask, during rotation of the spindle and flask, by said fluid actuated element, a source of fluid under pressure connected with said fluid pressure actuated element, said fluid pressure actuated element being disposed in heat transmitting relation with the head so that the fluid in said fluid pressure actuated element will tend to carry away heat absorbed by the head from castings being formed in the flask.

20. In a centrifugal casting machine, a rotatable flask of sleeve-like form and means for forming a sand mold within the flask, and including a shank portion rotatably supported on the machine and having an eccentric axle portion constituting a continuation of said shank portion, a roller journaled on said axle portion, said shank portion and said flask being supported for relative movement for causing insertion of said roller into said sleeve-like mold, and means for rotating said shank portion for displacing said eccentric axle portion for urging said roller into contact with the sand mold being formed in said flask.
